UNITED STATES PATENT OFFICE.

JAMES H. ROBBINS, OF DANSVILLE, NEW YORK, ASSIGNOR OF TWO-THIRDS
TO GEORGE D. TILLOTSON AND PATRICK O'CONNOR, OF SAME PLACE.

BUCKBOARD-WAGON.

SPECIFICATION forming part of Letters Patent No. 242,371, dated May 31, 1881.

Application filed October 12, 1880. (No model.)

To all whom it may concern:

Be it known that I, JAMES H. ROBBINS, of Dansville, Livingston county, New York, have invented a certain new and useful Improvement 5 in Buckboard-Wagons; and I do hereby declare that the following is a full, clear, and exact description of the same, reference being had to the accompanying drawings, in which—

Figure 1 is a plan of a buckboard-wagon, 10 showing my improvement applied thereto. Fig. 2 is an elevation of the front spring and its connecting parts. Figs. 3, 4, 5, and 6 are detail views.

My improvement relates to that class of vehicles known as "buckboard-wagons," and the invention consists in an improved arrangement of the joints connected with the half elliptic springs, as hereinafter more fully described.

20 In the drawings, A A represent the axles. B is the reach. C C are angular braces connecting the reach with the rear axle. D D are the half elliptic springs; and E E are the goose-necks, all of well-known form and construction.

25 My improvement is as follows:

G is a ball cast or formed on the upper end of each goose-neck, and preferably chilled or otherwise hardened. H is a socket which fits 30 and turns upon this ball, and is attached to the end of the spring. This socket is made in halves a a, which are counterparts, fitting face to face, as shown in the front view, Fig. 4. At the top the parts of the socket have ears b b, through which passes a screw, c, for clamping the parts together. At the bottom it has two lugs, d d, between which rests the eye f of the spring, and through which passes a bolt, g, forming the pivot to attach the spring and allow it proper play. The screw c and bolt g form the clamps at top and bottom to fasten the halves of the socket together and hold it upon the ball.

By the use of the ball and socket a universal joint action is secured, which enables the spring not only to turn laterally without binding, in the same manner that the knuckle does, but also to turn quartering, or at any angle between a longitudinal and crosswise direction. This is a very great advantage, as

the motions of the spring, under its vibrations, are such as to bring a quartering or angular twist upon the parts. At the same time the spring is allowed to expand and contract longitudinally by the employment of the lugs or 55 bearings d d, attached to the socket, and the pivot g, which passes through the same.

To allow the proper joint motion of the socket upon the ball, the eye h, through which the goose-neck passes, is made larger than the 60 goose-neck itself, so that the socket may move in any and all directions to the proper extent and without impediment.

By the means above described the greatest freedom is allowed to the spring in all directions, and it is prevented from rolling the axles. The construction of the socket in halves, with ears at top and bottom, the latter serving as the bearings for the spring, secures great cheapness and simplicity, and enables the 65 sockets to be attached upon the balls without difficulty. A ball and socket is used at each end of both the front and rear springs.

I and K represent two irons used at the front end of the wagon, the first being attached on the under side of the head-block or bolster J, and the last being attached on top of the spring D, with a leather or other suitable packing between. These plates have two circles, m m, of small diameter, which fit 80 together and turn one on the other. The lower circle has a concentric rib, n, on its top, which fits in a corresponding groove, o, of the upper circle. The lower circle has also a conical thimble, p, which projects upward through 85 an opening in the center of the upper circle. In the bottom of the lower iron, K, is a square socket, s, which extends but part way through and has a shoulder at the top. In this socket rest the heads v w of two bolts, M and N, the 90 first passing up through the thimble p, and thence up through the head-block, and serving to hold the spring to the head-block, and the latter passing through the leaves of the spring and serving to hold them together. 95 The upper iron, I, is attached to the head-block by means of bolts y y, and the lower one, K, is attached to the spring by clips z z.

I do not claim a knuckle turning laterally on a goose-neck and provided with a pivoted 100

link or clevis for receiving the end of the spring; but

What I claim is—

In a buckboard-wagon, the socket H, constructed in halves *a a*, fitting together on the ball G, and provided at their bottom with lugs *d d*, formed solid with the same, the lugs serving as the bearings for the spring, the socket being secured on the ball by means of a screw, *c*, at the top, and a bolt, *g*, at the bottom,

which latter also serves as the axis for the end of the spring, as herein shown and described.

In witness whereof I have hereunto signed my name in the presence of two subscribing witnesses.

JAMES H. ROBBINS.
